J. A. MCKAY,
ELECTRICAL FITTING CONNECTION,
APPLICATION FILED OCT. 25, 1919.

1,378,477.

Patented May 17, 1921.

Inventor
John Andrew McKay
By his Attorney
Joel B. Liberman

UNITED STATES PATENT OFFICE.

JOHN ANDREW MCKAY, OF NEW YORK, N. Y., ASSIGNOR TO GENERAL ELECTRIC COMPANY, A CORPORATION OF NEW YORK.

ELECTRICAL FITTING CONNECTION.

1,378,477.

Specification of Letters Patent. Patented May 17, 1921.

Application filed October 25, 1919. Serial No. 333,386.

To all whom it may concern:

Be it known that I, JOHN ANDREW MCKAY, a subject of the King of Great Britain, and resident of the city of New York, 5 county of New York, State of New York, have invented certain new and useful Improvements in Electrical Fitting Connections, of which the following is a specification.

10 The present invention relates to electrical fitting connections and is an improvement on the structure shown in Letters Patent Nos. 1300286 and 1307869. In said patents a pivotally mounted terminal member is 15 carried by a canopy and for this purpose the canopy is provided with special members to afford pivotal supporting means for the terminal member.

The main object and feature of the present invention is to admit of the use of standard fixtures, without necessity of alteration in connection with the invention of said Letters Patent. To this end, the bushing of the canopy is employed, the leads being 25 passed through it as a support for the mounting of the pivotally supported terminal member.

Other features of the invention will appear as the specification proceeds.

30 In the accompanying drawings the invention is shown in a concrete and preferred form, in which—

Figure 1 is a sectional view, on line 1--1 of Fig. 2, through a canopy and electrical 35 fitting connection embodying my invention.

Fig. 2 is a view in elevation of the parts shown in Fig. 1, looking in the direction of arrow of Fig. 1, the canopy being broken away and its outline indicated in dotted 40 lines.

Fig. 3 is a detail view, partly broken away, of the mounting for the terminal member with the latter indicated in dotted lines.

45 The mounting consists of two jaws 1 that are in superposed relation and connected by means of a pivot 2 so that they will open or close in a manner similar to that of a pair of scissors. Each jaw is provided with an 50 angularly extending lug 3 having an aperture 4. It will be seen that, when the jaws are swung into a given position, apertures 4, which constitute bearings for the terminal member 5, will be in alinement and the terminal 55 6 will enter said aperture. 7 indi-

cates an opening in each jaw and these openings are brought into register when the bearings for the pivotally supported terminal member are in alinement. 8 is a canopy of standard construction having a 60 bushing or hollow support 9. This bushing is introduced through openings 7, thereby preventing jaws 1 from swinging on pivot 2. 10 is a lock nut for holding the mount on the hollow support. 11 indicates 65 flexible connections, from the terminal member, that extend through bushing 9 of the canopy to the branches of an illuminating appliance as for instance a wall-bracket.

An advantage of the construction shown 70 resides in the fact that when the mounting is removed from the support, the pivotally supported terminal member may be quickly removed from the mounting by opening of the jaws. I have also found that the scissors feature of the device can be omitted 75 and a one part device with arms forced into the shell, but the advantages are obviously with the scissors construction.

I claim:

1. An electrical fitting comprising: a 80 mounting for a terminal member consisting of two superposed and pivotally connected jaws, an angularly extending lug carried by each jaw, said lugs having bearings that are 85 in alinement with each other when the jaws are swung into a given position, and a terminal member pivotally and removably supported in said bearings.

2. An electrical fitting comprising: a 90 mounting for a terminal member consisting of two superposed and pivotally connected jaws, an angularly extending lug carried by each jaw, said lugs having bearings that are 95 in alinement with each other when the jaws are swung into a given position, and a terminal member pivotally and removably supported in said bearings, and means for preventing the jaws from swinging on their pivot.

3. An electrical fitting comprising: a 100 mounting for a terminal member consisting of two superposed and pivotally connected jaws, an angularly extending lug carried by each jaw, said lugs having bearings that are 105 in alinement with each other when the jaws are swung into a given position and said jaws having openings that are in register when the bearings are brought into alinement, a support extending through the reg- 110

istered openings, means for receiving the jaws on the support and a terminal member pivotally supported in said bearings.

4. An electrical fitting comprising: a 5 mounting for a terminal member consisting of two superposed and pivotally connected jaws, an angularly extending lug carried by each jaw, said lugs having bearings that are in alinement with each other when the jaws 10 are swung into a given position, and said jaws having openings that are in register when the bearings are brought into alinement, a fixture support extending through the registered openings, means for securing the jaws to the support, a terminal member 15 pivotally supported in said bearings, and a flexible connection extending from the terminal member through the fixture support.

5. An electrical fitting comprising: a mounting for a terminal member consisting 20 of two superposed and pivotally connected jaws, an angularly extending lug carried by

each jaw, said lugs having bearings that are in alinement with each other when the jaws are swung into a given position and said jaws having openings that are in register 25 when the bearings are brought into alinement, a fixture support extending through the registered openings, means for securing the jaws to the support, a terminal member pivotally supported in said bearings, and a 30 flexible connection extending from the terminal member through the fixture support.

6. An electrical fitting comprising: a terminal member, a mounting having arms pivotally connected and carrying angularly 35 extending lugs, each lug having bearings adapted to pivotally support the terminal member.

Signed at New York city in the county of New York and State of New York, this 22 40 day of October, 1919.

JOHN ANDREW MCKAY.
